CONTROL KNOB

Herbert Morrison, Yonkers, N.Y., and George L. Schick,
New Canaan, and Paul O. Rawson, Trumbull, Conn.,
assignors to The Singer Company, Elizabeth, N.J., a
corporation of New Jersey

Filed Dec. 9, 1963, Ser. No. 77,715

Term of patent 14 years

(Cl. D70—2)

FIG. 1 is a top plan view of a control knob showing our new design,

FIG. 2 is a front elevational view of the control knob shown in FIG. 1,

FIG. 3 is a bottom plan view of the control knob shown in FIG. 1,

FIG. 4 is a right elevational view of the control knob shown in FIG. 1,

FIG. 5 is a left elevational view of the control knob shown in FIG. 1.

The essential features of our design reside in the portions shown in full lines.

We claim:

The ornamental design for a control knob, substantially as shown and described.
